DESIGN FOR A TRAILER VEHICLE

Frederick M. Reid, Detroit, Mich., assignor to Fruehauf Trailer Company, Detroit, Mich., a corporation of Michigan

Application November 1, 1937, Serial No. 72,569

Term of patent 3½ years

To all whom it may concern:

Be it known that I, Frederick M. Reid, a citizen of the United States, residing in Detroit, in the county of Wayne, State of Michigan, have invented a new, original, and ornamental Design for a Trailer Vehicle, of which the following is a specification, reference being had to the accompanying drawing, forming a part thereof, wherein:

Figure 1 is a side elevational view of a trailer vehicle showing my new design;

Fig. 2 is a front elevational view; and,
Fig. 3 is a rear elevational view.

I claim:

The ornamental design for a trailer vehicle as shown.

FREDERICK M. REID.
